UNITED STATES PATENT OFFICE

RUSSELL P. HERROLD, OF ZANESVILLE, OHIO

DESIGN FOR TILING

Application filed July 16, 1930. Serial No. 36,369. Term of patent 14 years.

To all whom it may concern:

Be it known that I, RUSSELL P. HERROLD, a citizen of the United States, residing in Zanesville, in the county of Muskingum and State of Ohio, have invented a new, original, and ornamental Design for Tiling, of which the following is a specification, reference being had to the accompanying drawing, forming part thereof.

The figure is a plan view of the tiling, showing my new design. The article illustrated, is a block of tile of conventional thickness.

I claim:

The ornamental design for a tiling, as shown and described.

RUSSELL P. HERROLD.
